COLOR APPLYING TOOL

Joseph R. Benkowski, Chicago, Ill., assignor to Wendell Manufacturing Company, Chicago, Ill., a corporation of Illinois

Filed Oct. 21, 1958, Ser. No. 768,652

2 Claims. (Cl. 120—42.6)

This invention relates to a color-applying tool for applying precious metal pigment colors, such as those embodying gold, silver and the like, to ceramic and other surfaces.

Various types of color-applying tools for applying precious metal pigment colors to ceramic surfaces have been known and used heretofore. However, one of the problems previously experienced in the use of such prior color applying tools has been the difficulty of controlling the flow of the pigment color through the striping tool to the ceramic or other work surface when the color-applying tool is not in use.

Accordingly, an object of the present invention is to provide a new and improved color-applying tool which is so constructed and arranged that it may be readily employed for applying precious metal pigment colors, such as those embodying gold, silver, and the like, to ceramic and other work surfaces while, at the same time, enabling the parts of the new color-applying tool to be readily manually adjusted to prevent leakage or flow of the pigment color when the tool is not in use.

Another object of the present invention is to provide in the new color-applying tool a novel manually controlled valve arrangement which is so designed and constructed that the parts of the new color-applying tool may be readily manually adjusted to prevent leakage or flow of the pigment color when the tool is not in use.

Other and further objects will appear hereinafter.

In the drawings:

Fig. 1 is an elevational view of a color-applying tool embodying the present invention;

Fig. 2 is a central longitudinal sectional view of the new color-applying tool shown in Fig. 1;

Fig. 3 is an enlarged fragmentary sectional detail view showing the novel valve arrangement embodied in the new color-applying tool;

Fig. 4 is a sectional plan view on line 4—4 in Fig. 2;

Fig. 5 is a sectional bottom plan view on line 5—5 in Fig. 2;

Fig. 6 is a central sectional view illustrating a modification of the invention; and

Fig. 7 is an exploded sectional view illustrating the parts embodied in the modified form of the invention illustrated in Fig. 6.

A preferred form of the present invention is illustrated in Figs. 1 to 5, inclusive, of the drawings, where it is generally indicated at 10, and includes a manually operable cylindrical combination rod and handle member 11 having an enlarged finger grip member 12 suitably secured thereon, as by means of a suitable adhesive. The new color-applying tool 10 includes a combination color-receiving and holding reservoir and tip member 13, which is generally conical in shape, and includes a lower end portion 14 of reduced diameter having a tip portion 15 which is open at its lower end and is internally threaded, as at 16. The plunger rod and handle member 11 has a reduced externally threaded lower end portion which is bifurcated to provide a pair of striping and color-applying

2

nib portions 17—18 formed therein at its lower end. These nib portions 17—18 are slightly separated from each other, as at 20, and the lower end portions 17—18 thereof are unthreaded and project outwardly of the open end reduced lower end portion 15 of the tip of the combination reservoir and tip member 13—14—15, as shown in Figs. 1, 2 and 3. The externally threaded lower end and nib portion 17 of the rod-handle member 11—12 is threadedly engaged with the internally threaded lower end portion 14—15 of the combination reservoir and tip member 13—14—15.

A valve seat is formed in the reduced lower end portion 15 of the combination reservoir and tip member 13—14 by providing an annular shoulder 21 on the inner surface thereof, and the rod and handle 11—12 has a shoulder 22 formed thereon, immediately above the internally threaded nib portion 17, and this shoulder 22 is engageable with the valve seat 21.

In the use of the form of the invention shown in Figs. 1 to 5, inclusive, the combination color-receiving reservoir and tip member 13 may be filled with precious metal pigment color, such as colors embodying gold, silver, or other precious metal pigments, for application to ceramic surfaces, and the like, and when so filled the rod and handle member 11—12 will be initially positioned so that the annular shoulder 22 thereon engages the valve seat 21 and thus prevents flow of the color from the reservoir 13 into the passage 20 between the nib portions 17—18 when the tool is not in use.

However, when it is desired to use the new color-applying tool, as shown in Figs. 1 to 5, inclusive, the rod and handle member 11—12 may be retracted upwardly by manually rotating the same so as to raise the annular shoulder 22 above the valve seat 21, whereupon color will flow from the body of the combination reservoir and tip member 13 down through the lower end portion 14—15 thereof into the space 20 between the nib portions 17—18 and thence onto the surface of a ceramic material or other work.

It will thus be noted that when the new color-applying tool is not in use it may be arranged in upright position in a suitable support, with the annular shoulder 22 engaging the valve seat 21, and when the parts are so arranged, leakage of the color will be prevented, thus overcoming a difficulty experienced in the use of the prior art color-applying tools.

In the form of the invention illustrated in Figs. 6 and 7 of the drawings those parts which are similar to corresponding parts of the invention illustrated in Figs. 1 to 5, inclusive, of the drawings, have been given similar reference numerals followed by the additional and distinguishing reference character "a."

The form of the invention illustrated in Figs. 6 and 7 of the drawings includes a relatively small storage receptacle 26 for precious metal pigment colors, such as those embodying gold, silver and the like. This storage receptacle 26 has a frusto-conical shaped upper end portion 27, having an open upper end, and an externally threaded reduced lower end portion 28 which has a central passage 29 formed therein communicating with the interior 30 of the frusto-conical shaped upper end portion 27.

The form of the invention illustrated in Figs. 6 and 7 of the drawings also includes an internally threaded main coupling member 31, which has an internally threaded frusto-conical shaped passage 32 formed therein, and this form of the invention also includes an auxiliary coupling member or adapter 33.

The auxiliary coupling member or adapter 33 is externally threaded, as at 34, and has an internally threaded central passage 35 of reduced diameter, formed in its upper end portion, and a relatively wider and unthreaded central lower internal passage 36 formed therein.

An annular gasket 37, having a central passage 38, is arranged between the upper end wall 39 of the combination reservoir and tip member 13a and the lower end wall 40 of the auxiliary coupling member 33, as shown in Fig. 6.

A conventional guide member 41 may be swingingly mounted in a boss 43 formed in the wall of the main coupling member 31 for guiding the color-applying tool over the work, such as a ceramic surface 43, as is well understood in the art.

In the use of the form of the invention illustrated in Figs. 6 and 7 of the drawings the parts may be assembled as shown. This is accomplished by inserting the combination reservoir and tip member 13a-14a-15a into the lower end portion of the frusto-conical shaped central central passage 32 of the main coupling member 31, in which it will rest as shown in Fig. 6, with the gasket 37 resting on the upper end wall 39 of the tip member 13a-14a-15a. The auxiliary coupling member 33 may then be secured in the threaded upper portion of the central passage 32 in the main coupling member 31 and the threaded lower end portion 28 of the reservoir or receptacle 26 then threadedly inserted into the threaded passage 35 in the auxiliary coupling member 33.

The rod and handle member 11a may then be inserted through the central passage 30-35-36-30 in the parts 26-33-37 with the nib portions 17a-18a threaded into the threaded lower end portion 19a of the combination reservoir and tip member 13a and with the shoulder 22a thereon engaging the valve seat 21a. The color may then be poured into the reservoir 26 through the open upper end thereof, whereupon it will flow by gravity down through the central passage 30-29-35-36-38 into the upper portion of the reservoir 13a in which it will be retained by the engagement of the annular shoulder 22a on the rod-handle member with the valve seat 21a.

When it is desired to use the new color-applying tool shown in Figs. 6 and 7 the plunger rod and handle member 11a may be manually rotated to retract the annular shoulder 22a from the valve seat 21a, whereupon the color will flow from the upper portion of the reservoir 13a past the valve seat 21a and thence between the nibs 17a-18a onto the work.

It will thus be seen from the foregoing description, considered in conjunction with the accompanying draw-

ings, that the present invention provides a new and improved color-applying tool having the desirable advantages and characteristics, and accomplishing its intended objects, including those hereinbefore pointed out, and others which are inherent in the invention.

I claim:

1. A color-applying tool especially adapted for applying precious metal pigment colors to ceramics and other work surfaces and comprising a generally hollow frusto-conical shaped combination color reservoir and tip member including an apical portion having a tapered internally threaded bore formed therethrough and having an annular shoulder formed therein on its inner surface inwardly of said internally threaded bore and providing a valve seat, a manually operable rod and handle member extending through said combination color reservoir and tip member and having a bifurcated externally threaded outer end portion providing a pair of nib portions threaded into the said internally threaded bore, each of said nib portions including an end portion extending from the outer end of the bore, said rod and handle member having an annular shoulder formed thereon inwardly of said externally threaded outer end portion thereof and said annular shoulder being adapted to be removably engaged with said valve seat by manual rotation of said rod and handle member so as to control flow of color from said combination color reservoir and tip member into said bore and between and onto said nib portions, the portion of said combination color reservoir and tip member remote from said apical portion being open to receive colors to be applied.
2. A color applying tool as defined in claim 1, in which each of said nib portions has an unthreaded outer end portion normally extending outwardly beyond the apical portion of said combination color reservoir and tip member.
